UNITED STATES PATENT OFFICE

2,601,906

DISCHARGE ELECTRODE SYSTEM FOR
ELECTRICAL PRECIPITATORS

Harry A. Winternmute, Plainfield, N. J., assignor
to Research Corporation, New York, N. Y., a
corporation of New York

Application January 29, 1951, Serial No. 208,327

7 Claims. (Cl. 183—7)

1

This invention relates to electrical precipitation apparatus for the separation of suspended materials from gases.

More particularly the invention relates to means for substantially eliminating or damping oscillation and swinging of flexible discharge electrodes in Cottrell type precipitators.

In most Cottrell type precipitators the discharge electrodes are long flexible electrical conductive members suspended from their upper ends between collecting electrodes. These flexible discharge electrode members are held taut by a weight at their lower ends, and commonly, where there are a plurality of discharge electrodes, they are tied together by means of a spacing framework or bar loosely engaging each of the electrodes just above the weights.

While this construction affords a very satisfactory arrangement of supporting and centering discharge electrodes, the combination of long flexible electrodes with heavy weights at their lower ends will swing as a pendulum unless restrained.

Swinging of the electrodes appears to be caused by gas flow, changes in gas conditions and in electrical operation. For example, a change in the relative humidity or moisture content of the gases to be cleaned has been found to initiate swinging, or the swinging may be started by the combined action of movement of gas through the treating zone of the precipitator and the electrical field maintained between the discharge and collecting electrodes. Generally the oscillation of the electrode system starts with a low amplitude and gradually increases until a heavy arcing condition has been established between the discharge and collecting electrodes thus greatly lowering the efficiency of the precipitator.

In the past insulating supports have been used between the precipitator wall and the spacing framework, or the discharge electrodes have been made of stiff material to damp oscillation. However, neither of these methods have proved very satisfactory, as the stiff electrodes have a tendency to act as springs and maintain rather than damp the oscillation, and when insulators are used for steadyng they are adjacent the point of maximum fall of precipitate which often forms a conductive layer upon the insulators.

It is therefore a principal object of the invention to provide means for substantially preventing and damping the periodic swinging and oscillation of flexible discharge electrodes, thus permitting the electrical precipitation apparatus to be operated with greater efficiency and at a higher potential than heretofore possible.

2

These and other objects and advantages are provided by the damping system of the invention which in its preferred embodiment comprises a weight means flexibly suspended from the discharge electrode system of an electrical precipitator at spaced points below the center of gravity of the discharge electrode system, supplemented when additional damping is desired by the provision of conductive grounded members spaced from said weights by a distance greater than the spacing between the discharge and collecting electrodes. The weight means may comprise a plurality of weight members or a single elongated weight member flexibly suspended from at least two spaced points.

The invention will be more particularly described with reference to the illustrative embodiments of the invention shown in the accompanying drawings, in which:

Fig. 1 is a fragmentary, vertical section of a horizontal flow plate type precipitator employing discharge electrode damping means constructed in accordance with the principles of the invention;

Fig. 2 is a vertical section of a vertical flow tubular type precipitator having discharge electrode damping means similar to those shown in Fig. 1 of the drawings; and

Fig. 3 is a section on line 3—3 of Fig. 2 to more clearly show the electrode spacing frame and oscillation damping weights.

With reference to the drawings, and in particular to Fig. 1, 10 is the shell or casing of the precipitator having a horizontal gas inlet 12, gas outlet 14, and dust storage hopper 16.

Within the casing are a plurality of plate type collecting electrodes 18, supported from the side walls of the casing, for example, by brackets 20.

The flexible discharge electrodes 22 are suspended between the collecting plates from the insulated electrode frame 24. Frame 24 in turn is supported by the high tension insulated lead-in 26.

At the lower end of each electrode are individual tension weights 28, and a spacing bar or guide frame 29. The guide frame 29 is loosely supported by the wire electrodes and prevents the electrodes from independently swinging or oscillating. Frame 29, however, has no restraining force to prevent free swinging of the entire group—electrodes, weights, and frame—in a straight line or orbital path, the limits of which are the collecting electrodes or the precipitator casing.

It has been found that auxiliary weights 30 flexibly suspended by cables 32 from the lower

spacing frame below the center of mass of the system will substantially eliminate and damp both linear and arcuate swinging of the discharge electrode system. As shown in the drawings, at least two damping weights spaced a substantial distance apart are necessary. One weight suspended below the center of mass of the discharge electrode group will only damp linear oscillation, as the single suspended weight will form a pivot point around which the electrode system will oscillate in an arcuate path. The greater the distance between the flexibly suspended damping weights the greater will be their damping effect on the torsional pendulation of the system. The point about which the system will tend to rotate will lie midway between the damping weights, thus by increasing the radius of swing of the damping weights, the force required to set them in motion is increased.

On installations where the forces creating the pendulation of the discharge electrodes is great or where additional steadyng means are required it has been found that if an electric field is formed between the damping weights 30 and a conductive member secured to the precipitator frame even less oscillation will occur in the electrode system.

In the form of the invention shown in Fig. 1 of the drawing, adjacent each of the damping weights 30 are grounded bars 34 supported, for example, by a frame 36 carried by the side walls of the dust hopper. The distance between the weights 30 and bars 34 is greater than the arc ing distance of the highest electrical potential adapted to be used in a given installation. Thus while no arcing occurs between bars 34 and weights 30 a strong electrostatic field is developed there-between which tends to resist any relative movement between these members.

Referring to Figs. 2 and 3 of the illustrative embodiments of the invention there is shown a vertical flow tubular type electrical precipitator in which 100 is the casing of the apparatus, comprising a precipitated material storage zone 102, gas treating zone 104 and the header zone 106. Opening into the casing are the collected material outlet 108, gas inlet 110 and clean gas outlet 112.

Within the casing are a plurality of tubular collecting electrodes 114 supported from a plate 116 which separates the gas treating and outlet zones of the precipitator.

Centrally disposed within each collecting electrode is a flexible wire discharge electrode 118 suspended from the electrode support and bus bar 120. At the lower end of each wire electrode 118 are individual tension weights 122. Adjacent the weights a tie and spacing bar or frame 124 is loosely supported by the wire electrodes. The form of the spacing frame is more clearly shown in Fig. 3 of the drawing.

As hereinbefore mentioned in relation to the form of the invention shown in Fig. 1 of the drawings, the entire discharge assembly comprising electrodes, weights and frame are free to swing in a straight line or path and any direct restraining means for the system presents a difficult problem of insulation due to the high electrical potential maintained in an electrostatic precipitator between the discharge and collecting electrodes. In accordance with the principles of the invention this difficulty is ob viated by flexibly suspending at least two spaced weights below the center of mass of the discharge

electrode system and where needed providing an electrostatic field between the suspended damping weights and an adjacent grounded member.

The damping weights, designated 126, are supported by electrically conductive cables 128 attached to the electrode spacing frame 124. Adjacent each of the damping weights 126 there may be placed a grounded bar 130 supported, for example, by a frame 132 carried by the side walls of the dust hopper, when added damping is desired by means of the electrostatic field developed between the grounded bars and the damping weights.

From the foregoing description it will be seen that the present invention provides a novel electrode oscillation damping means, whereby the aims, objects and advantages of the invention are fully accomplished.

It will be evident that various modifications may be made in the construction of the device. For example, it is contemplated that the electrostatic field damping device may be used with or without the primary damping weights and that additional damping of the electrode system will be obtainable by employment of an electrostatic field between grounded members and the electrode spacing frame or the individual tension weights or both.

I claim:

1. A discharge electrode system for electrical precipitators comprising a plurality of discharge electrodes movably suspended from a support, means for holding the electrodes in spaced relation and weight means flexibly suspended therefrom at spaced points below the plane of the electrode holding means, whereby the center of mass of the flexibly suspended weight means is below the center of gravity of the discharge electrode system.

2. A discharge electrode system for electrical precipitators comprising a plurality of discharge electrodes movably suspended from a support, means for holding the electrodes in spaced relation, and a plurality of weights flexibly suspended therefrom at spaced points below the lower active ends of the discharge electrodes, whereby the center of mass of the flexibly suspended weights is below the center of gravity of the discharge electrode system.

3. A discharge electrode system for electrical precipitators comprising a plurality of discharge electrodes movably suspended from a support, a spacing frame near the lower end of the electrodes for holding the electrodes in spaced relation, and at least two weights flexibly suspended at spaced points from the spacing frame below the plane of said spacing frame whereby the center of mass of the flexibly suspended weights is below the center of gravity of the electrode system.

4. A discharge electrode system for electrical precipitators comprising a plurality of discharge electrodes movably suspended from a support, a spacing frame suspended near the lower end of the electrodes for holding the electrodes in spaced relation, tension weights attached at the lower ends of the electrodes, and at least two damping weights flexibly suspended at spaced points from the spacing frame below the tension weights, whereby the center of mass of the damping weights is below the center of gravity of the electrode system.

5. A discharge electrode system for electrical precipitators comprising a plurality of discharge electrodes movably suspended from a support,

means for holding the electrodes in spaced relation, a plurality of weights flexibly suspended at spaced points from the spacing frame below the center of gravity of the electrode system, and conductive grounded members spaced from said weights by a distance greater than the spacing between the discharge and collecting electrodes of the electrical precipitator.

6. A discharge electrode system for electrical precipitators comprising a plurality of discharge electrodes movably suspended from a support, a spacing frame near the lower end of the electrodes for holding the electrodes in spaced relation, at least two weights flexibly suspended at spaced points from the spacing frame below the center of gravity of the electrode system, and conductive grounded members spaced from said weights by a distance greater than the spacing between the discharge and collecting electrodes of the electrical precipitator.

7. A discharge electrode system for electrical precipitators comprising a plurality of discharge electrodes movably suspended from a support, a

spacing frame suspended near the lower end of the electrodes for holding the electrodes in spaced relation, tension weights attached at the lower ends of the electrodes, at least two damping weights flexibly suspended at spaced points from the spacing frame below the center of gravity of the electrode system, and conductive grounded members spaced from the damping weights by a distance greater than the spacing between the discharge and collecting electrodes of the electrical precipitator.

HARRY A. WINTERMUTE.
